SEAM FOR GARMENTS

Max C. Schrank, Bridgeton, N. J.

Application June 14, 1934, Serial No. 730,671

1 Claim. (Cl. 2—275)

In the manufacture of clothing and particularly underwear for women and girls, it is of high importance to reduce cost of manufacture to the minimum and especially in regard to labor costs and at the same time not impair the style and other qualities, essential in the feminine mind in articles of underwear. And all this is especially true having reference to the present vogue in women's apparel which calls for garment reduction to the minimum. An object of my present invention is to achieve the conflicting requirements of reduction of cost of manufacture and the preservation of the style and practical utility of the garment. And my invention concerns underslips especially.

It will be found from the description of the embodiments of my invention hereinafter given that seams are reduced in number compared with similar garments heretofore.

The seams resist tearing strains, and there is snug or close fit at the bust of the wearer.

My invention consists in whatever is described by or is included within the terms or scope of the appended claim.

25 In the drawing:

Fig. 1 is a view in perspective of a slip embodying my invention viewed from the front, with a torn-away portion;

Fig. 2 is a similar view of another embodiment 30 of my invention;

Figs. 3 and 4 are, respectively, plan views of the cut-out blanks or pieces of cloth for making the slips shown in Figs. 1 and 2;

Fig. 5 is a detail view in horizontal section on 35 a large scale through one of the seams.

Describing in detail what is shown in Figs. 1 and 3 of the drawing, the waist or body portion 10, and the skirt 11, including the shadow-proof member 12, are in one integral piece, these parts 40 being included in the one-piece blank shown in Fig. 3 which is substantially L-shaped due to the lateral projection from what is one side of the skirt, of the shadow-proof forming overlap 12. The waist or body portion 10, consists of front 45 13 and back 14, that are substantially duplicate, the opposite side edges of each portion being shaped on curves to approximate the contour of the wearer's body and when folded or doubled over on a median line 15, the then adjoining

50 curved edges are sewed from top to the waist line, or a little below, to provide side seams 16, there being no seams elsewhere except the horizontal line of stitching 17, at the junction of the waist and skirt that joins the top edge of 55 the shadow-proof forming overlap 12, to the

garment at the waist line, or below the waist line, such stitching 17 being to the back 14.

It will be evident that cost of manufacture of the slip shown in Figs. 1 and 3, especially on account of labor, may be very low.

The cloth or fabric when cut to form the blank shown in Fig. 3 is so cut that the grain, that is to say, the strong warp threads W extend horizontally and the weft threads vertically. It has been found that when the raw edges are sewed together to form the seam with the warp threads at right angles to such edges, the warp threads give such body and resistance to the pull of the threads as to prevent the threads tearing out under strains in wearing the garment which the 10 weft threads are incapable of resisting. This is a matter of great practical importance especially because of the sheer fabrics of which slips are made and especially when they are made of artificial silk. To supplement the strengthening of 15 the seams by the cut as before explained, the form of seam shown best in Fig. 5 has been invented.

The raw edge of the fabric cut on the straight is folded over to form the lap L, shown in Fig. 5 and upon the thus overlapped portions a piece 25 of fabric B, cut on the bias is laid and through the overlying portions the stitching thread T is passed. Such a form of seam contributes materially to resist ripping or tearing strains and even alone provides a seam able to resist such 30 tearing or ripping strains as overcome ordinarily employed seam construction.

Preferably there is a hem 18, at the bottom of the skirt formed by folding over the lower edge and a hem 19, at the top which latter may 35 be conveniently formed of folded over separately made straight strips.

As shown in Fig. 1, the lower portion of the front 13 is free at its vertical edge from the opposite edge of the back 14, where the overlap 40 12 joins the latter so that there may be free movement of the overlying lower portions of the back and front to accommodate the movements of the leg of the wearer. The vertical edge of the overlap 12 opposite the connection with the 45 overlap with the back 14, is loose or free from the line of stitching 17 down to the bottom edge of the overlap.

The slip embodying my invention shown in Figs. 2 and 4 differs from that shown in Figs. 1 50 and 3 in that the shadow-proof overlap portion 12, while shown as made integral with the skirt portion, may be a separately cut, rectangular piece sewed at one edge to one side of the waist or body and skirt-forming portion of the blank. 55

so that as will be seen that, as indicated in dotted lines in Fig. 4, two such rectangular portions may be formed from a single piece by a median line cut C. And the top of the slip instead of 5 being the simple or severe straight formation of the slip of Figs. 1 and 3 is more fancy in that the top portion of both front and back are cut each to a pointed form, and the small trapezoid-like pieces 20, are respectively sewed to the inclined 10 sides of the point to make a built-up upper part to the waist which includes upwardly extending pointed portions that overlie the shoulders at the arms at front and back and which provide a V at front and back. A downwardly extending 15 tuck or dart 21, may be made at each side of the front to give a good fit of the garment. If desired, the slip may have a V-front and straight back, or a V-front and V-back.

The trapezoid-like pieces 20 are necessarily 20 from their method of production illustrated in Fig. 4, cut on the bias and as they constitute Fig. 4, cut on the bias and as they constitute the bust-covering portions of the slip, it follows

that being on the bias, they fit snugly and closely to the form. The skirt portion of the slip is cut on the straight and not on the bias and preferably with the warp threads extending horizontally.

Certain matter appears in this application common to the disclosure of my application No. 702,757 filed December 16, 1933 and as to the matters in common this application is to be considered a continuation in part of that.

What I claim is:

A garment made of pieces joined together by a seam formed by overlapping raw edges of the two pieces, one of such pieces having its edge doubled over upon itself, such piece being cut 15 on the straight and the other piece cut on the bias and the overlapped portions being joined by stitching that passes through all of them, the piece which is on the bias remaining unfolded at the seam.

MAX C. SCHRANK.
